RELAY

Carl J. Warnke, Elkhart, Ind., assignor, by direct and mesne assignments, to The Adams & Westlake Company, Chicago, Ill., a corporation of Illinois

Application June 12, 1931, Serial No. 543,843

10 Claims. (Cl. 200—90)

My invention relates to a relay for use under conditions requiring the periodic operation of local mechanisms, such as alarms and signals of various types, as exemplified in railway crossing signals, beacons for air ports, lighthouses, and devices of a similar operative nature, but is also utilizable for regulating the operation of other types of mechanisms whose timed control is desirable.

16 One object of my invention is to devise a relay which utilizes the principle of the pendulum in conjunction with a mercury switch to effect the operation of a given mechanism at periodic intervals.

15 A further object is to provide a relay of the character indicated employing a mercury switch mounted on a pendulum whose movement is controlled electromagnetically in each direction, the attainment of the maximum amplitude by the 20 pendulum in any one direction determining the operation of one device controlled by the relay, and causing a deenergization of that electromagnet which has just moved the pendulum in the indicated direction, with an energization of another electromagnet for moving the pendulum to the opposite end of its swing and the effecting of a similar manner of operation, including the 25 actuation of another device.

30 A further object is to provide a relay as above set forth in which provision is made for varying the oscillatory period of the pendulum in order to vary the periodic operation of the devices controlled by the relay, and to accomplish this result either by interposing a predetermined braking 35 resistance to the movement of the pendulum, or by varying the length of the pendulum, or by a combination of these factors, thereby rendering a standard type more versatile in its application and capable of functioning under a variety 40 of operating conditions.

45 A further object is to devise a relay which incorporates a factor of safety when used in connection with a dual signal or alarm system in that a failure of one signal or alarm does not affect the operation of the other, and further, in which the mercury switch is so arranged, that its failure, as by a cracking of the container thereof, results in a spreading of the mercury to such an extent as to complete the circuit to all 50 signals or alarms, thereby insuring their constant operation until the switch is replaced.

55 A further object is the provision of a relay which is characterized by ruggedness in construction, long life, positive, efficient and dependable operation, and which is capable of use under

conditions demanding precision in the frequency of the devices controlled.

These and further objects of my invention will be set forth in the following specification, reference being had to the accompanying drawings, 5 and the novel means by which said objects are effectuated will be definitely pointed out in the claims.

In the drawings:

Figure 1 is a plan view of my improved relay 10 partly in section;

Figs. 2 and 3 are sections along the lines 2—2 and 3—3 of Fig. 1, respectively, looking in the direction of the arrows;

Fig. 4 illustrates the wiring diagram as used 15 in connection with my improved relay, the pendulum being shown as occupying a vertical position;

Fig. 5 is a sectional elevation of the lower portion of the switch, being a view similar to that 20 shown in Fig. 3, but illustrating a modified disposition of the mercury pool in which the lower end of the pendulum swings;

Fig. 6 is an elevation of the pendulum as it appears in Fig. 3, but showing a suggested means 25 for varying the length of the pendulum in order to vary its period.

Fig. 7 is a sectional elevation of a modified type of switch, corresponding to the switch as viewed in Fig. 3, and showing the pendulum and mercury switch as constituting a separable, hermetically sealed unit.

Fig. 8 is an enlarged section taken on the line 35 8—8 in Fig. 7, looking in the direction of the arrows, and showing the manner in which the 35 electrical conductors from the mercury switch are led out of the hermetically sealed, pendulum unit.

Fig. 9 is a sectional view of still another form of relay, corresponding to that shown in Fig. 7, 40 in which provision is made for sealing the electromagnet, in addition to the pendulum unit, thereby enabling the relay to be used under subaqueous conditions.

Referring to Figs. 1, 2 and 3 of the drawings, 45 the numeral 10 designates the base of my improved relay which is generally of a hollow construction comprising an integral top 11 and a removable, bottom, cover-plate 12. An insulating strip 13 is recessed into the top 11 adjacent 50 one side of the base 10 and disposed along said strip is a group of binding posts 14, to which more particular reference will be hereinafter made. A substantially circular shoulder 15 is offset upwardly from the top 11 and around the periph- 55

ery of said shoulder is placed a sealing gasket 16. The lower, peripheral edge of an inverted, glass cylinder 17 is rested on the gasket 16 and fits closely the peripheral edge of the shoulder 15.

5 Extending downwardly through the top of the cylinder 17 is a screw 18, between the head of which and the top of said cylinder a sealing gasket 19 may be interposed. The lower end of the screw 18 is threadedly received in a spider 20
10 10 which is provided with a pair of oppositely disposed arms 21 and 22, and also with a second pair of oppositely disposed arms 23 and 24 (see Fig. 1), these respective pairs of arms being normally disposed to each other. The upper end of a hollow standard 25 is fixedly received within a pocket 26 provided in the branch 23 and the upper end of a standard 27 is similarly received within a pocket 28 provided in the branch 24, the lower ends of said standards being also fixedly mounted
15 20 in the shoulder 15. Communication between the interior of the standards 25 and 27 and the interior of the base 10 is effected by means of holes 29 and 30, respectively, for a purpose hereinafter explained. From the above it will be understood
25 that a tightening of the screw 18 will so position the cylinder 17 as to substantially hermetically seal the latter.

Suspended from the underside of the arm 21 is an electromagnet which is composed of a solenoid coil 31 and a metallic solenoid 32 extending through the center of said core and suitably insulated from the arm 21. Another electromagnet is suspended from the underside of the arm 22 and comprises a solenoid coil 33, through which 30 35 also extends a metallic core 34 that is insulated from said arm. This disposition of the solenoid coils 31 and 33 provides a space therebetween and within this space is mounted a pendulum mechanism which will now be described.

40 Extending downwardly from the spider 20 and substantially midway between the solenoid coils is a boss 35 which is drilled to receive the coiled end of a flexible, springy strip 36 and said end may be maintained in position by means of a headed pin 37. The lower end of the strip 36 is 45 also coiled for reception within a similar hole provided in the upper end of a pendulum 38 and is likewise maintained in position by means of a pin 39. The arrangement of the spring strip 36 substantially follows the standard practice in 50 the mounting of pendulums and in and of itself forms no part of the present invention. Other constructions may be employed as desired. At an elevation which is slightly below the lower 55 ends of the solenoid cores 32 and 34, the pendulum 38 is provided with a laterally extending arm 40 which is intended to function as the armature for the core 32 and also with a lateral extending arm 41 which performs a similar service with reference to the core 34. Below the armature arms 40 and 41, the pendulum carries a suitable clamp 42 which receives the tube or container 43 of a mercury switch 44.

The container 43 is hermetically sealed in accordance with standard practice and is provided with three wells 45, 46 and 47 which project downwardly from the lower side thereof, each of said wells constantly carrying a mass of mercury (see Fig. 4). Electrical connection in the normal operation of the switch between any two of the pools of mercury contained in the aforesaid wells is provided by a mass of mercury 48 which at all times provides an electrical connection between two of the pools in the said wells. Electrodes 49, 70 75 50 and 51 project within the pools of mercury

which are carried in the wells 45, 46 and 47, respectively, and said electrodes are connected externally of the circuit in a manner hereinafter described.

5 Except for the suggested details of construction as just given, the particular arrangement of the switch 44 forms no part of this invention, but it is contemplated that the switch will follow modern practice in the selection of a material for the tube 43 which will effectually withstand the shock and erosive action of the electric arc and be substantially free of occluded gases, will employ substantially pure mercury, a heat dissipating and arc-supressing gas fill, and electrodes which will present substantially clean surfaces to 10 the mercury during contact, and which will in general be of such a construction as to prevent any silvering action of the mercury on the electrodes or the walls of the container.

15 Below the switch 44, the pendulum 38, which is preferably in the form of a flat strip with its broadest side presented to view, as it appears in Fig. 3, extends downwardly toward the shoulder 15 and at some convenient distance from the lower end thereof is given a right angle twist to provide a paddle portion 52 which moves in a mercury pool 53 that is contained in a basin 54 attached to the shoulder 15.

20 In describing the electrical connections between the several parts of the relay, it will be assumed that the latter is used as an agent for controlling the illumination of a pair of lamps, such as are used as warning signals at railway crossings, the lamps alternately flashing according to a given frequency. In the binding post group 14, 30 the posts 55 and 56 constitute the in-put terminals of the relay and they may be connected externally of the latter with a suitable source of electrical energy, such as a battery 57 and also with a switch 58 which is arranged in series 35 therewith. For a railway crossing signal, the function of the switch 58 would be literally performed by the approach of a train which would serve to close the circuit between the binding posts 55 and 56 externally of the relay, although, 40 it will be understood, that in other operative situations, the switch 58 may be actuated manually or may be automatically controlled by other devices. The binding post 55 is electrically connected by means of a lead 59 with one end of the 45 solenoid coil 31 and the opposite end of said coil is connected by a lead 60 with a binding post 61, and the latter is in turn connected by a lead 62 with the electrode 49. The electrical connection between the binding posts 55 and 61 though the 50 coil 31 is effected by wires which are retained within the glass cylinder 17 and the base 10, one of the standards 25 or 27 being utilized as a convenient casing for holding the indicated wires. Externally of the relay, a lamp 63, which constitutes one of the warning signals is connected in parallel with the solenoid coil 31 across the 55 terminals 55 and 61.

60 On the opposite side of the pendulum 38, a lead 64 connects the binding post 55 with one end 65 of the solenoid coil 33 and the opposite end of said coil is connected to a binding post 65 by means of a lead 66, said post being in turn connected to the electrode 51 by a lead 67. A second lamp 68 is connected in parallel with the coil 33 between 70 the posts 55 and 65, the connections for said lamp being disposed externally of the relay in the same manner as for the lamp 63. A common return lead 69 connects the binding post 56 with a binding post 70 and said lead, together with all 75

others which are connected either to the coils 31 and 33 or to the electrodes of the mercury switch are conveniently led through the standards 25 and 27 in order to provide a satisfactory 5 housing for these wires and also to improve the general appearance of the relay.

In describing the operation of the relay, it will be assumed that the pendulum occupies the vertical and motionless position shown in Fig. 4, with the switch 58 open, the latter for the conditions under discussion, being generally representative of a railway train. Owing to the fact that the switch 58 is open, neither of the lamps 63 and 68 will be ignited, nor will either of the coils 31 and 33 be energized. However, the mercury mass 48 will occupy an electrically connecting position between the pools in the wells 45 and 46, for example, or it may connect the similar pools in the wells 46 and 47. Fig. 4, however, shows the former condition by way of illustration.

When an approaching train reaches a predetermined position from the railway crossing, the condition then obtaining will be that which would follow upon a closing of the switch 58. Thereupon, the lamp 63 will be illuminated and the coil 31 energized, since the return circuit in the battery 57 is completed through the mercury switch 44 by the mercury mass 48. The energizing of the coil 31 attracts the armature arm 40 and thereby initiates movement of the pendulum 38 toward the left, as viewed in Fig. 4, and when the latter has moved through a sufficient amplitude the mercury mass 48 will move towards the right end of the container 43 to thereby break the electrical circuit through the switch between the electrodes 49 and 50 and to complete the circuit between the electrodes 50 and 51. When this condition occurs, the lamp 63 is extinguished and the coil 31 is deenergized, while the coil 33 is energized and the lamp 68 is illuminated. The armature arm 41 is thereupon drawn towards the core 34 by the combined effect of gravity and the magnetic action, so that the pendulum moves toward the right as viewed in Fig. 4. Upon or shortly before attaining its maximum amplitude in the latter direction, as determined by the space relation of the several parts, the mercury mass 48 will move toward the left, as viewed in Fig. 4, and will eventually reach its left maximum position under the reenergization of the coil 31 thus completing one period of the pendulum, considering the beginning of the period as being the moment when the pendulum starts its swing towards the right. As long as the switch 58 is maintained closed, the pendulum 38 swings between the electromagnets in equal times and therefore causes a periodic illumination of the lamps 63 and 68 alternately.

The purpose of the mercury pool 53 is to provide a means of conveniently varying the period of the pendulum through interposing a predetermined braking resistance to its swinging action. By varying the depth of the mercury 53, the resistance interposed to the movement of the paddle 52 will accordingly be varied, so that within certain definite limits, the period of the pendulum may be adjusted to provide any desired flashing frequency of the lamps 63 and 68. The use of mercury is suggested as a convenient fluid for obtaining the desired effect on the swinging movement of the pendulum, owing to its non-evaporative characteristic, but it will be apparent that other fluids may be employed if desired, and that, in addition to varying the depth of the fluid employed in order to vary the resistive ac-

tion on the paddle 52, other variations may be secured by selecting fluids having different densities.

A still further means of varying the period of the pendulum is shown in Fig. 6, this method depending upon the principle that the period or time of oscillation of any pendulum is directly proportional to its length. In this modification, the pendulum 38 is composed of an upper part 72, to which is secured the branches 40 and 41 and below said branches the part 72 is bifurcated to provide a pair of spaced limbs 73. The upper end of the lower part 74 of the pendulum is received between the limbs 73 and said upper part may be provided with an elongated slot 75 through which 10 and the limbs 73 passes a clamping or adjusting screw 76. According to this arrangement, therefore, the lower part 74 may be shifted vertically to provide any desired length of the pendulum as a unit within the maximum adjustability 20 of the device.

A further modification of the relay is illustrated in Fig. 5. One objection to the form shown in Figs. 1 to 3, inclusive, is that, when the relay is shipped from the factory with mercury in the 25 basin 54, the relay unit must be handled with care and maintained in an upright position at all times in order to retain the mercury in said basin. The modification in Fig. 5 has been designed with a view of overcoming this objection. Specifically, the base 10 is provided with a substantially circular shoulder 11 which is offset upwardly from the top 11 and the upper surface of the shoulder 11 is dished, as at 18, to present a surface which is concave upwardly. A well 19 is 35 formed in the central portion of the shoulder 11 to receive a mass of mercury 80, or other suitable fluid, and within said fluid mass operates the lower end of the pendulum 38 as above described. Since the glass cylinder 17 is hermetically 40 sealed to the base 10, the relay modification shown in Fig. 5 may be turned end for end or on its side without risking the loss of the fluid in the well 19, but upon placing the relay in its proper upright position, as shown in said figure, the 45 conformation of the shoulder 11 will at once cause the fluid 80 to drain in the well 19.

In the modifications shown in Figs. 7 and 8, the switch is also provided with a base 10 having an integral top 11 and the removable, bottom, cover- 50 plate 12, together with the series of binding posts as shown in Fig. 2. Attached to the top 11 is the flanged bottom 81 of a hermetically sealed casing 82, the top of which is closed by a cover 83. Said casing and its cover may be composed 55 of any suitable non-magnetic material, but will in any case be hermetically sealed and will be preferably filled with a neutral or reducing gas, such as hydrogen, carbon-monoxide, nitrogen, or the like, for the purpose of arresting oxidation 60 of the pool of mercury 84 which is carried by and normally rests on the curved portion 85 of the bottom 81.

Intermediate the ends of the cover 83 and extending downwardly from the underside thereof 65 is a boss 86 which is drilled to receive the coiled end of a flexible, springy strip 87 whose lower end is also coiled for reception within a similar hole provided in the upper end of a pendulum 88, both ends of said strip being maintained in 70 position in the manner described in connection with the switch shown in Fig. 2. Below the connection of the spring 87 with the pendulum 88, the latter is provided with a pair of laterally extending arms 89 and 90, each of which adjacent 75

their respective ends is provided with an armature boss 91 which extends upwardly towards the cover 83. Below the arms 89 and 90 the pendulum 88 is formed substantially the same as 5 is the pendulum shown in Fig. 2, that is, it comprises a paddle portion 92 which normally dips in the mercury mass 84 and also carries a mercury switch 93 which is generally similar to the switch 43 and likewise comprises the three depending wells 94. The electrical conductors 95 which 10 lead from the wells 94 are passed through the wall of the casing 82 in the manner shown generally in Fig. 8. As shown in said figure, the metallic portions 96 of said conductors are sealed 15 in glass insulators 97 generally after the manner now in common use in introducing electrical conductors into incandescent lamp bulbs, or mercury switch containers, the insulators 97 themselves being in turn sealed in any approved manner 20 to the wall of the casing 82. After passing through the wall of the casing 82, the conductors 95 may be connected to the binding posts shown in Fig. 2.

A pair of electromagnets are disposed above 25 the cover 83, one being composed of a solenoid coil 98 and a metallic core 98^a extending therethrough, the lower end of said core contacting with, or being relatively close to, the cover 83 in the region of the upper end of the left armature 30 boss, as viewed in Fig. 7. Similarly, the other electromagnet 99 is provided with a metallic core 100 and the lower end of said core is similarly disposed with reference to the cover 83 and the upper end of the left armature boss 91, also as 35 viewed in Fig. 7. The electromagnets are supported from the underside of a spider 101 which is in turn carried on the upper ends of standards 102, which are similar to the standards 25 and 27 shown in Fig. 2. As in the preceding switches, 40 the entire assembly may be enclosed by a cylindrical case 103 whose lower edge rests upon a gasket 104 and is maintained in this position by means of a cap screw 105 carried by the case 103 and whose lower end is threaded in the spider 101.

45 The operation of this modified form of switch, as well as the plan of its electrical connections, is identical with the switch shown in Fig. 2, the magnetic field being alternately established by the electromagnets operating through the non-magnetic cover 83 and also across the intervening air gap in order to establish the swinging movement of the pendulum 88. By forming the casing 82 and its contents as a hermetically sealed unit with an appropriate neutral gas enclosed therein, any tendency of the mercury mass 84 to become oxidized is obviated and it also provides an easily replaceable unit for purposes of repair. Also, as in the type of switch illustrated in Fig. 5, it is unnecessary to maintain the entire 50 relay in an upright position during transit in order to retain the mercury in the bottom of the casing. As soon as the entire assembly is placed in the position shown in Fig. 7, the mercury will again collect in the bottom of the base 81.

55 In Fig. 9 is shown a modified form of the switch illustrated in Fig. 7. This modification also employs the hermetically sealed casing 82, together with its pendulum-mercury switch content, but in addition, makes provision for also hermetically 60 sealing the electromagnet unit of the switch, so that the latter may be effectually used under water. As shown in said figure, the electromagnets are enclosed by a case 106 which may rest upon or be otherwise attached to the casing 82 65 or the cover 83 thereof as desired, but whatever

the type of attachment, it is contemplated that the connection between the casing 106 and the casing 103 will be of a sealed nature.

While I have shown one set of elements and combinations thereof for effectuating my improved relay, it will be understood that the same is intended for purpose of illustration only and in no wise to restrict my device to the exact forms and structures shown, for many changes may be made therein without departing from the spirit 10 of my invention.

I claim:

1. A relay having in combination, a unit comprising a hermetically sealed casing, a pendulum swingably mounted in said casing, a mercury switch carried on said pendulum and means for breaking the swing of the pendulum comprising a pool of mercury in which the lower end of the pendulum swings, and electromagnetic means located externally of said casing for controlling the swing of said pendulum, said electromagnetic means being hermetically sealed within a second casing.

2. A relay having in combination a pair of hermetically sealed, superimposed casings, one of said casings comprising a pendulum swingably mounted therein, a mercury switch carried by said pendulum, and means for breaking the swing of the pendulum comprising a pool of mercury in which the lower end of the pendulum swings, and the other of said casings enclosing electromagnetic means for controlling the swing of said pendulum, the magnetic fields established by said electromagnetic means operating through the non-magnetic walls of said casing.

3. In a device of the class described, a base, a pair of standards rising from the base, a spider mounted on the standards and having a plurality of arms, two of which engage the tops of the standards, and electromagnetic means supported 40 by two other arms of the spider.

4. In a device of the class described, a base, a pair of standards rising from the base, a spider mounted on the standards and having a plurality of arms, two of which engage the tops of the standards, electromagnetic means supported by two other arms of the spider, and a pendulum suspended from said spider between the standards.

5. In a device of the class described, a base, a pair of standards rising from the base, a spider mounted on the standards and having a plurality of arms, two of which engage the tops of the standards, electromagnetic means supported by two other arms of the spider, and a pendulum suspended from said spider between the standards, said pendulum having laterally extending, rigid, armature arms coacting with the electromagnetic means for swinging the pendulum.

6. In a device of the class described, a base, a pair of standards rising from the base, a spider mounted on the standards and having a plurality of arms, two of which engage the tops of the standards, electromagnetic means supported by two other arms of the spider, and a pendulum suspended from said spider between the standards, said pendulum having laterally extending, rigid, armature arms coacting with the electromagnetic means for swinging the pendulum, and a mercury switch mounted on the pendulum controlling the electromagnetic means.

7. In a device of the class described, a base, intermittent circuit breaking mechanism including a pair of standards rising from the base,

- 5 a spider mounted on the standards, a pendulum suspended from the spider between the standards, coils carried by the spider for swinging the pendulum, a bell jar mounted on the base and enclosing the mechanism, and means for hermetically sealing the bell jar in place, said means including a screw passing through the top of the jar and threaded into the spider.
8. In a device of the class described, a base, 10 intermittent circuit breaking mechanism including a pair of standards rising from the base, a spider mounted on the standards, a pendulum suspended from the spider between the standards, coils carried by the spider for swinging the pendulum, a bell jar mounted on the base and enclosing the mechanism, the upper face of the base having a pocket for receiving a fluid, and an inwardly sloping rim around the pocket, the end of said pendulum being adapted to swing within said pocket, and be retarded by 15 the fluid in the pocket.
10. In a device of the class described, the combination of a hollow base, a pair of hollow standards mounted on the base and communicating with the base interior, a spider mounted 15 on the standards having a plurality of arms, two of which engage the tops of the standards, electromagnetic means supported by two other arms of the spider, and a pendulum suspended from the spider between the standards and adapted 20 to be swung by the electromagnetic means.
9. In a device of the class described, a base, 20

intermittent circuit breaking mechanism including means for supporting a pendulum over said base, electromagnetic means for swinging the pendulum including a mercury switch carried by the pendulum, a bell jar mounted on the base and enclosing the mechanism, the upper face of the base having a pocket for receiving a fluid, and an inwardly sloping rim surrounding the pocket, the ends of said pendulum being adapted to swing within said pocket, and be retarded by 10 the fluid in the pocket.
